W. F. DEAN

POWDER PUFF

Filed Jan. 25, 1922

Inventor

William F. Dean,

By George A. Barnard,

Attorney

UNITED STATES PATENT OFFICE.

WILLIAM F. DEAN, OF JOHNSTOWN, NEW YORK, ASSIGNOR TO GOLUN FUR NOVELTY CO., OF JOHNSTOWN, NEW YORK, A PARTNERSHIP COMPOSED OF WILLIAM F. DEAN, FRED LUNKENHEIMER, AND WILLIAM GOULD.

POWDER PUFF.

Application filed January 25, 1922. Serial No. 531,534.

To all whom it may concern:

Be it known that I, WILLIAM F. DEAN, a citizen of the United States, residing at Johnstown, in the county of Fulton and State of New York, have invented certain new and useful Improvements in Powder Puffs; and I do hereby declare the following to be a full, clear, and exact description of the invention, such as will enable others skilled in the art to which it appertains to make and use the same.

My invention relates to powder puffs and has for its object to provide a powder puff which may be easily carried in a bag or in the pocket.

Another object of my invention is to provide a powder puff, the puff proper being made of leather tanned with the fur thereon, thus avoiding any unnecessary stitches. In my preferred form, I employ lamb's skin, the wool of which has not been removed.

Still another object of my invention is to provide a powder puff which may be folded upon itself and fastened, thereby taking up as little space as possible.

With the above and other objects in view which will appear as the description proceeds, my invention consists of the novel features herein set forth, illustrated in the accompanying drawing and more particularly pointed out in the appended claims.

In the drawing, numerals of like character designate the same parts throughout the several views.

Fig. 1 is a view of the main portion, before the wool portion shown in Fig. 1^a is attached.

Fig. 1^a is a view of the back of the wool portion showing the perforations through which the powder is admitted to the wool.

Fig. 2 shows the powder puff completed but not folded.

Fig. 3 is a cross section of Fig. 2.

Fig. 4 is a front view of the powder puff folded for carrying.

Fig. 5 is a side view of Fig. 4.

1 designates the main portion of the powder puff which is made of a circular piece of lamb's hide with the wool removed and provided with a flap 2 integral therewith. The flap 2 and the lower portion of the circular piece 1 are provided with snaps 3, 4 and 5. The snap 3 is adapted to engage the outer portion of the snap 5 when the device

is folded, and the snap 4 engages the snap 5 in the wool portion 6. This wool portion 6 is provided with perforations 7 through the hide thereof to permit the powder to pass into the wool, when the portion 6 is stitched to the main portion 1. This is accomplished by placing the wool portion 6 on the main portion 1 with the wool facing upwardly (as shown in Fig. 2) and then stitching the circumference of the circular portions, leaving the space x—x open and forming a pocket 9 for the insertion of the powder.

At the top of the wool portion 6, I provide a strip of tape 8 which is held in place by the snap 4^a, and which is adapted to be used in unfastening the snaps 4 and 4^a when it is desired to fill the pocket of the powder puff.

When the powder is inserted through the opening x—x, the snaps 4 and 4^a are fastened together and the powder is secured in the pocket 9 between the main portion and the wool portion as shown in Fig. 3.

When the powder puff is put in use, the powder will pass through the perforations 7 into the wool and thence onto the skin of the user.

It is to be noted, in the use of sheep or lamb's wool, that close to the hide there is a layer of fine slightly curly hair which forms within the wool comprising the sheet material adopted by applicant for the application of the fine dry toilet powder, an automatically acting and self regulating feed for the powder into and through the main body of the wool upon the face or body of the user, so that the supply of powder will be just sufficient for use.

In order to fold the device, the lower portion is rolled up and the snap 3 is pressed over the snap 5, as shown in Figs. 4 and 5.

What I claim and desire to secure by Letters Patent is:—

1. A powder distributor comprising a flexible main back portion, a flexible front portion, means for securing the two portions together to form a pocket and leaving a filling space for said pocket through which the powder may be inserted in the pocket, the flexible front portion consisting of sheep skin tanned with the wool thereon and provided with perforations through which the powder may pass, the wool of the skin auto-

matically operating to regulate the movement of the powder through the perforations.

2. A powder distributor comprising a flexible main back portion having an elongated flap, a flexible front portion formed of sheep or lamb skin with the wool thereon, the two portions being stitched together at their meeting edges forming a pocket, provided with an opening at the base of the flap

for the insertion of powder, the said front portion being provided with perforations for the escape of powder through the wool, and fastening means on the flap, back portion and front portion whereby the opening for the insertion may be closed, and the pocket folded upon itself.

In testimony whereof I affix my signature.

WILLIAM F. DEAN.
